UNITED STATES PATENT OFFICE.

ANDREW G. WEAVER AND RALPH E. RAWSON, OF STOCKTON, CALIFORNIA.

TRACTOR HITCH FOR SCRAPERS.

Application filed December 9, 1924. Serial No. 754,734.

To all whom it may concern:

Be it known that we, ANDREW G. WEAVER and RALPH E. RAWSON, citizens of the United States of America, residing at Stockton, county of San Joaquin, State of California, have invented certain new and useful Improvements in Tractor Hitches for Scrapers; and we do declare the following to be a full, clear, and exact description of same, reference being had to the accompanying drawings, and to the characters of reference marked thereon, which form a part of this application.

This invention relates to improvements in means for controlling the operation of scrapers, and especially to a device for controlling a scraper of the well known Fresno type from the driver's seat of a tractor attached to and hauling the scraper.

The principal object of this invention is to provide a device of this character by means of which the driver of the tractor, without leaving his seat, may manipulate the scraper to cause the same to load, carry, spread or dump without having to halt or back-up the tractor while so doing.

Another object of the invention is to construct a device for the purpose in such a manner that it may be easily and quickly attached to any scraper of the above named type without making any changes or alterations thereto, and without the use of any tools, other than a standard monkey wrench, being necessary, since certain bolts, etc., already provided on the scraper are used in attaching our device thereto.

A further object of the invention is to produce a simple and inexpensive device and yet one which will be exceedingly effective for the purposes for which it is designed.

These objects we accomplish by means of such structure and relative arrangement of parts as will fully appear by a perusal of the following specification and claims.

In the drawings similar characters of reference indicate corresponding parts in the several views:

Fig. 1 is a perspective outline of a tractor attached to a scraper provided with our hitch and control means, the scraper being in loading position.

Fig. 2 is a side elevation of the scraper in carrying position.

Fig. 3 is a sectional elevation of the same in a dumping position.

Referring now more particularly to the

characters of reference on the drawings, the scraper comprises a bowl 1 having a scraping blade 2 and side plates 3. Side supports 4 having shoes or runners 4^a are secured to the plates 3 by bolts 5 and project upwardly and forwardly of the bowl when the latter is in its normal or scraping position. Links 6 to which draft means are ordinarily connected, are detachably mounted on the inside of the plates 3. These parts are standard in scrapers of the aforementioned type and we do not alter the same in any way.

Our hitch and control attachment, applied to such standard structure, comprises rigid beams 7 pivoted at their rear ends on the links 6 and converge to a junction with each other at their forward ends, at which ends said beams are secured together in connection with plates 8 to form a clevis for attachment to the draw head 9 of a tractor 10.

Extending transversely of the scraper a certain distance ahead of the same is a shaft 11 which is turnably mounted in bearing boxes 12 fixed on the beams 7. Arms 13 extend radially from said shaft at the ends thereof and are connected by links 14 to the forward ends of rigid straps 15 which extend forwardly from the side plates 3 substantially in alinement with the lower portions of the supports 4. These straps are rigidly secured to the plates 3 by means of the adjacent bolts 5 of said shoe supports 4. The forward ends of the straps 15 terminate just behind the normally vertical portion of the supports 4 so that when the shoes on said supports turn to a horizontal position to ride on the ground, the straps do not dig into the ground.

The arms 13 are so positioned that when the scraper is in its normal or scraping position, the outer ends of said arms and the straps 15 are about in vertical alinement with each other, and the links 14 are therefore vertically disposed.

Another arm 16 projects radially from the shaft 11 intermediate the ends thereof and is disposed substantially at right angles to the arms 13. To the arm 16 is connected a lever 17 which extends forwardly to a point adjacent the front end of the beams 7 and at its forward end is formed with a loop 18 or the like to serve as a handle and as a means for attaching one end of a rope 19 to the lever. The lever 17 is angularly adjustable on the arm 16 so as to enable the setting of said lever relative to the arms 13.

to be altered to suit different operating conditions.

In operation with the tractor hauling the scraper the lever 17 is allowed to raise somewhat, which causes the links 14 to be lowered. This in turn causes the blade 2 to bite into the ground, since the bowl with the forward movement of the tractor swings on the pivotal connection of the beams 7 with 10 the links 6 as an axis.

As soon as the blade engages the ground the operator reverses the direction of pressure on the lever and maintains a downwardly directed pressure thereon, since 15 otherwise the forward movement of the tractor would cause the scraper to dump.

To carry a load scraped the operator depresses the lever down about as far as possible toward the beams 7, the links 14 being 20 then raised, and consequently the blade also. The bowl of the scraper to the rear of the blade then of course rides on the ground, as shown in Fig. 2.

When a load is to be spread or dumped 25 the operator releases the holding-down pressure on the lever, while maintaining control over the same by means of the rope 19. With a continued forward movement of the tractor the bowl will rock forwardly, the 30 arms 13 moving down and the lever 17 moving rearwardly until the scraper rides on the shoes 4^a. For spreading, the rear movement is restricted so that the space between the forward edge of the blade 2 and the 35 ground is suitable for this purpose. For dumping the lever is allowed to move without restriction, since the usual adjustable cross-beam 21 on the members 4^a will ultimately bear against the beams 7 to limit the 40 rotation of the bowl.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of 50 the invention, as defined by the appended claims.

Having thus described our invention what we claim as new and useful and desire to secure by Letters Patent is:

1. A hitch and control attachment for scrapers comprising a rigid structure adapted to be pivotally mounted at its rear end onto the sides of the scraper and at its forward end to be connected to a draft 55 means, a lever mounted on said structure and arranged to be controlled from the draft means, and means connected to the 60

lever and adapted to be attached to the scraper whereby the latter may be moved to and held in any position by pressure on 65 said lever in a continuous direction and with the forward movement of the scraper.

2. A hitch and control attachment for scrapers comprising a rigid structure adapted to be pivotally mounted at its rear end 70 onto the sides of the scraper and at its forward end to be connected to a draft means, a transverse shaft journaled in a fixed position on said structure, a lever extending from said shaft and controllable from the 75 front of the scraper, arms projecting from the shaft in a plane at an angle to that of the lever, and means adapted to be attached to the scraper and extending thence to the arms arranged to enable rotation of the 80 scraper about said rigid structure as induced by the forward movement of the scraper to be controlled at all positions through the medium of movement of the lever.

3. A hitch and control attachment for 85 scrapers comprising a rigid structure adapted to be pivotally mounted at its rear end onto the sides of the scraper and at its forward end to be connected to a draft means, a transverse shaft journaled in a fixed position on said structure, a lever extending from said shaft and controllable from the 90 front of the scraper, arms projecting from the shaft in a plane at an angle to that of the lever, rigid straps extending forwardly 95 from and adapted to be secured to the sides of the scraper, and links between the outer ends of the straps and arms.

4. A structure as in claim 3, in which said links, when the scraper is in a normal 100 scraping position, being substantially vertically disposed and the lever then projecting forwardly at an acute angle to a point adjacent the front end of the rigid structure.

5. A hitch and control attachment for 105 scrapers having side plates and shoe supports bolted thereon, and draft links connected thereto, comprising a rigid beam structure adapted at one end to be attached to a draft means, and at the other to be 110 pivoted on said links, a transverse shaft journaled on said structure, a lever for controlling the rotation of said shaft, arms projecting radially from the shaft, rigid straps projecting forwardly from the side 115 plates of the scraper and adapted to be secured thereto by the adjacent bolts of the shoe-supports, and links between the outer ends of said straps and arms.

In testimony whereof we affix our signatures.

ANDREW G. WEAVER.
RALPH E. RAWSON.
